J. F. O'BRIEN.
ENGAGING AND DISENGAGING GEAR FOR SHIPS' BOATS.
APPLICATION FILED JULY 26, 1918.
1,298,777. Patented Apr. 1, 1919.

UNITED STATES PATENT OFFICE.

JOSEPH F. O'BRIEN, OF WEST NEW YORK, NEW JERSEY.

ENGAGING AND DISENGAGING GEAR FOR SHIPS' BOATS.

1,298,777.

Specification of Letters Patent.

Patented Apr. 1, 1919.

Application filed July 26, 1918. Serial No. 246,844.

To all whom it may concern:

Be it known that I, JOSEPH F. O'BRIEN, a citizen of the United States, and resident of West New York, in the county of Hudson and State of New Jersey, have invented certain new and useful Improvements in Engaging and Disengaging Gear for Ships' Boats, of which the following is a specification.

10 This invention relates to improvements in engaging and disengaging gear for ships' boats.

A rapid and positive freeing automatically of the boat from the falls is a great desideratum in life saving equipment, and the primary object of this invention is to produce a gear embodying hook members supported or mounted at opposite ends of the boat, each of which has a weighted releasing member 20 adapted to automatically release so soon as the load on the hook caused by the pressure or strain due to the suspension of the boat from such hook is relieved. This release is caused by a movement of the hook member 25 and releasing member in the same direction from loaded to releasing positions. Such a release will of course take place when a boat suspended from the hooks is water-borne.

Another object of my invention is to produce a hook which will under the circumstances above outlined release with great speed and positiveness and will eliminate all liability of sticking, jamming or tangling of connecting parts.

35 Another object of said invention is to simplify the construction of such hooks and so to dispose the parts thereof as to eliminate the necessity of machine work and accurate adjustments of such parts.

40 More particularly my invention comprises the production of a gear composed of a hook, comprising a shank portion, a shackle seat portion, and a bill portion, arranged to permit the shackle or ring of the falls to be inserted and seated within the hook, in combination with a releasing member having one end pivoted to the bill of the hook and having its opposite end free, extending rearwardly in the direction of the movement of the hook when releasing and provided with a suitable weight at its free end. Said releasing member is adapted to contact with the tackle or ring of the falls by which the boat is suspended and is sensitive to the pres-

ence or absence of the load on said hook, and 55 preferably has an arched portion intermediate its weight and pivot which contacts, as aforesaid, with the shackle ring. When so organized, said releasing member is adapted so soon as pressure is relieved from the 60 shackle ring, as for example when the boat is waterborne, to move downwardly and forwardly relatively to the hook, but moves the hook in the same rearward direction as the hook is compelled to move in when releasing, 65 whereby the hook will be released from engagement with the ring. The movement of the lever or releasing member caused by the weight will be downward in the direction in which the shackle ring is also moving. 70

In the accompanying drawing in which similar reference characters designate corresponding parts throughout the several views—

75 Figure 1 is a side elevation of the releasing device showing, in full lines, the position of the device in engagement with the shackle or falls-ring, under load, and also engaged with the mousing loop; and in dotted lines illustrating the position of the device when set for engagement with the shackle;

Fig. 2, is a front elevation of the device shown in Fig. 1, in engagement with the shackle but not with the mousing loop.

Fig. 3, is a plan view of the hook shown in 85 Figs. 1 and 2 in loaded position with the mousing loop in locking engagement;

Fig. 4, is a side elevation of the device shown in Figs. 1 to 3 in released position;

Fig. 5, is a front elevation of a modified 90 form of device embodying my invention; and

Fig. 6, is a plan view of said modified form shown in Fig. 5.

Referring now to Figs. 1 to 4 of these 95 drawings,

1 indicates the hook of my gear, having, as shown, a shank portion 1^a, a shackle-seat portion 1^b, and a bill portion 1^c. The hook is suitably supported on a boat 2, and, as 100 illustrated is pivoted to swing to opposite sides of a vertical plane on a pivot-pin 3, mounted in a bearing bracket 4.

Pivoted to the bill 1^c of the hook at 5^a, and having a free end extending rearwardly beyond the shackle seat 1^b and preferably beyond the shank 1^a of said hook, is a releasing-member 5, provided at its free rear-

wardly-extending end with a suitable weight 6. Said lever 5, has, intermediate said weight and its pivot, an arched portion 7, which, as illustrated, corresponds in con-
5 formation with the bill and a portion of the shackle-seat of the hook, and is also preferably provided with an elbow or toe-portion 8, at the rear of said arched portion 7, which assists during releasing movement in forcing
10 the shackle outwardly.

The hook 1 is limited in its pivotal movement in opposite directions by means of a pin 9, fixed in the bearing bracket 4 and co-operating with abutments 10—10^a formed
15 at opposite sides on the base of the hook whereby the hook is permitted to move from the set position shown in dotted lines in Fig. 1 to the releasing position shown in Fig. 4.

20 In order to produce a symmetrical gear and to provide means for guiding the releasing member, I preferably bifurcate either the releasing member or the hook member and cause one of such members to be seated within the other. In the preferred embodiment of my invention shown in Figs. 1 to 4, the releasing member or lever is bifurcated as at 5^b and has its bifurcated portion extending on opposite
25 sides of the hook and abutting against the bill, shackle-seat and shank portions thereof.

In the modified form of my invention shown in Figs. 5 and 6, the hook member 11 is bifurcated beginning at its shank
35 portion 11^a. This bifurcation includes the shackle seat and bill portion, and the weighted releasing member is seated centrally between such bifurcated portions and pivoted to the said bill portion at 12. This form of
40 hook may also be provided at its lower end with a knuckle seat into which fits a bearing knuckle 13. The parts are pivotally connected by a pivot pin 14 and the hook is limited in its movements by the pin 15
45 fixed in the knuckle 13.

In both constructions the releasing member is preferably provided with an extension lip 16 at the front side of the pivot which is adapted to co-operate with a loop
50 17 pivoted at its lower end at a fixed point, as, for example, to a bearing projection 17^a on the bearing bracket 4, for the purpose of mousing the hook as indicated in Fig. 1.

The operation of the device is as follows:
55 To secure the hook, it is preferably moved into the set position indicated in dotted lines in Fig. 1, the shackle-ring 18 is placed beneath the device and hoisted up till the loaded position of the device shown in full
60 line in said Fig. 1 is reached. The hook now being loaded the boat to which it is attached may be lowered over the side of the ship. So soon as the load is relieved from the hook, as, for example, when the boat is
65 waterborne, the releasing-member will be

caused by its weight 6, to move downwardly around its pivot and in substantially the same direction in which the load is traveling, and this downward movement simultaneously transmits rearward movement 70 through the pivot 5^a to the hook, which is caused to swing backwardly on its pivot pin 3 carrying the releasing-member therewith, and this movement of the hook and releasing members in the same direction causes an 75 exceptionally quick and positive release and eliminates the passing through the tackle ring of any loose or flexible parts which are likely to stick or become jammed or to cause a tangling during the releasing movement 80 or thereafter.

Under certain conditions, it may be desirable to mouse an automatically-actuated hook, and for this purpose the pivoted mousing loop 17 is simply swung over the 85 extension lip or hook 16, whereupon the shackle will be quickly and safely locked by the weight 6 within the hook but may be readily released by a tilting of the weight. When the hook is so locked, the shackle 90 cannot escape as is the case when a hook is moused by means of a rope, lanyard or other flexible device.

Having described my invention I claim:

1. In gear for engaging and disengaging 95 the shackle from ships' boats, the combination with a hook and means for suitably supporting the same on a boat, of a releasing member pivoted at one of its ends to the front of the hook and having a free opposite end extending rearwardly from said pivot, and means at said free end for causing said lever to swing on its pivot and eject the shackle ring from the mouth of the hook when pressure is relieved therefrom. 100

2. In a gear for engaging and disengaging the shackle from ships' boats, the combination with a hook and means for pivotally supporting the same on a ship's boat, of a releasing lever having one end pivoted at 110 the bill of the hook and its opposite end free and extending rearwardly, and a suitable weight at said rear end to cause the movement of the hook and lever in the same direction from engaging to releasing position. 115

3. In a gear for engaging and disengaging the shackle from ships' boats, the combination with a hook having a bill, a ring-seat portion and a shank portion, and means for pivotally supporting the same on a ship's boat, of a releasing-lever having one end pivoted at the bill of the hook, an intermediate contact portion and its opposite end free and extending rearwardly beyond the 120 shank of the hook and provided with a suitable weight at said free end to cause the said lever to be moved downwardly and forwardly and to transmit movement through the pivot to the hook to cause the same to 125 130

move backwardly away from the shackle-ring and to carry the lever therewith.

4. In a gear for engaging and disengaging the shackle from ships' boats, the combination with a hook having a bill, a ring-seat portion and a shank portion, and means for pivotally supporting the same on a ship's boat, of a releasing lever having one end pivoted at the bill of the hook and its opposite end free and extending rearwardly beyond the shank of the hook and provided with a suitable weight at said free end to cause the said lever to be moved downwardly and forwardly and to transmit movement through the pivot to the hook to cause the same to move backwardly away from the shackle ring and to carry the lever therewith, and a metallic mousing device adapted to close the mouth of the hook when the same is in loaded position.

5. In a gear for engaging and disengaging the shackle from ships' boats, the combination with a hook having a bill, a ring-seat portion and a shank portion, and means for pivotally supporting the same on a ship's boat, of a releasing lever having one end pivoted at the bill of the hook and its opposite end free and extending rearwardly beyond the shank of the hook and provided with a suitable weight at said free end to cause the said lever to be moved downwardly and forwardly and to transmit movement through the pivot to the hook to cause the same to move backwardly away from the shackle ring and to carry the lever therewith, one of said members being bifurcated and the other seated within said bifurcated member.

6. In a gear for engaging and disengaging the shackle from ships' boats, the combination with a hook and means for pivotally supporting the same on a ship's boat, said hook having a shackle-seat, a bill portion and a shank portion, of a releasing member comprising a lever having one end pivoted at the bill of said hook and its opposite end free and extending rearwardly beyond the shank of said hook, said lever being provided with a suitable weight at said free end whereby the releasing lever and hook are caused to swing rearwardly away from the shackle to releasing position, and means on said shank portion for limiting the pivotal movement of said hook.

- 55 7. In a gear for engaging and disengaging the shackle from ships' boats, the combination with a hook and means for pivotally supporting the same on a ship's boat, said hook having a shackle-seat, a bill portion and a shank portion, of a releasing member comprising a lever having one end pivoted at the bill of said hook and its opposite end free and extending rearwardly beyond the shank of said hook, said lever being provided with a suitable weight at said free end

and a shackle-contacting portion intermediate said pivot and weight, and coöperating means on said shank and supporting means for limiting the movement of the hook.

8. In a gear for engaging and disengaging the shackle from ships' boats, the combination with a hook and means for pivotally supporting the same on a ship's boat, said hook having a shackle-seat, a bill portion and a shank portion, of a releasing member comprising a lever having one end pivoted at the bill of said hook and its opposite end free and extending rearwardly beyond the shank of said hook, said lever being provided with a suitable weight at said free end and a shackle-contacting portion arched to conform in shape with a part of the shackle-seat of the hook and located intermediate its pivot and weight.

9. In a gear for engaging and disengaging the shackle from ships' boats, the combination with a hook and means for pivotally supporting the same on a ship's boat, said hook having a shackle-seat, a bill portion and a shank portion, of a releasing member comprising a lever having one end pivoted at the bill of said hook and its opposite end free and extending rearwardly beyond the shank of said hook, said lever being provided with a suitable weight at said free end and a shackle-contacting portion located intermediate its pivot and weight and being arched to conform in shape with a part of the shackle seat of the hook and having an elbow at its rear end extending within the shank of the hook.

10. In a gear for engaging and disengaging the shackle from ships' boats, the combination with a hook and means for pivotally supporting the same on a ship's boat, of a releasing lever having one end pivoted at the bill of the hook and its opposite end free and extending rearwardly and a suitable weight at said rear end; a short extension at the front side of said pivot, and mousing means pivoted contiguous to the base of the hook and adapted to engage said extension.

11. In a gear for engaging and disengaging the shackle from ships' boats, the combination with a hook and means for pivotally supporting the same on a ship's boat, of a releasing lever having one end pivoted at the bill of the hook and its opposite end free and extending rearwardly and a suitable weight at said rear end; a short extension at the front side of said pivot, and a metallic mousing loop pivoted at a fixed point at its lower end and engaging said extension at its upper end.

12. In a gear for engaging and disengaging the shackle from ships' boats, the combination with a hook and means for pivotally supporting the same on a ship's boat, of a releasing lever having one end pivoted at the bill of the hook and its opposite end free and

extending rearwardly and a suitable weight at said rear end; an extension having a hooked portion at the front side of said pivot, and a metallic loop pivoted at a fixed point at its lower end and engaging said hook at its upper end.

Signed at the borough of Manhattan, city

of New York, in the county of New York and State of New York this 25th day of July A. D. 1918.

JOSEPH F. O'BRIEN.
